FUEL DISTRIBUTOR

Paul A. Ketchpel, West Englewood, N. J., assignor,
by mesne assignments, to The Standard Stoker
Company, Inc., a corporation of Delaware

Application October 26, 1933, Serial No. 695,334

13 Claims. (Cl. 110—101)

My invention relates to fuel distributing mechanism for mechanical stokers and more particularly to the type of distributing mechanism which is made in two or more separable sections.

It is the main object of the invention to provide an improved two section distributing mechanism, and more specifically it is an object to provide such mechanism wherein the one section is constructed in the form of a pressure fluid jet head and the other section in the form of a distributing table, each of said sections having means formed therewith permitting engagement or disengagement of the sections in a novel, convenient and simple manner.

A further object of the invention consists in so forming the engaging portions of the table section and the head section as to restrain relative lateral and longitudinal movement therebetween and permitting pivotal movement of said table section upwardly with respect to said head section to a position permitting disengagement of said sections.

Other objects and advantages of the invention will become apparent from the following description and the accompanying drawings. The invention has been described and illustrated as applied to a locomotive stoker but it will be clear that the invention is not necessarily restricted and may be applied to advantage to other forms of stokers.

Referring to the drawings,

Figure 1 is a central vertical longitudinal sectional view taken on the line 1—1 of Figure 2 through a portion of the backwall of a locomotive firebox and the forward portion of a stoker with the novel distributing mechanism applied thereto and shown in similar section;

Figure 2 is a sectional view taken on the line 2—2 of Figure 1;

Figure 3 is a sectional view taken on the line 3—3 of Figure 2;

Figure 4 is a plan view of a modified form of the distributing mechanism;

Figure 5 is a sectional view taken on the line 5—5 of Figure 4; and

Figure 6 is an enlarged fragmentary sectional view taken on the line 6—6 of Figure 4.

Wherever the terms "front" and "rear" appear in the following description and claims, it should be understood that they are applied in the sense in which they are used on a locomotive.

With reference particularly to the form of construction illustrated in Figures 1, 2 and 3, there is shown at 10 a portion of the rear wall of a locomotive boiler firebox having a firing opening 11 therethrough. A portion of a stoker for deliver-

ing fuel to the firing opening 11 is shown at 12 and comprises the screw 13 housed within the inclined stoker conduit 14 which opens endwise into the firing opening. That portion of the stoker extending rearward of the conduit 14 to the tender or other source of fuel supply forms no part of the present invention and may be of any suitable conventional construction and has therefore not been shown in the drawings. Any preferred construction may be employed for attaching the conduit 14 to the wall 10 to maintain the conduit mouth portion 15 in communication with the firing opening 11.

The bottom of the mouth portion 15 is open between the sidewalls 16 and 17 and forward of the ledge 18. A chambered casting or distributor head 19 of the distributing mechanism is provided with a flat upper surface 20 and is detachably disposed in the open bottom of the mouth portion 15 to form in effect a floor portion for the delivery end of the conduit 14. A plurality of spaced jet openings 21 extend across the upright face 22 of the distributor head 19 in a horizontal row and communicate with one or more chambers 23 formed within the distributor head 19.

A distributing table 24 extends forwardly from the distributor head 19 and is attached thereto in a novel manner which will be hereinafter described in detail. Steam or any other suitable fluid under pressure is supplied to the chambers 23 through suitable openings near the lower end of the distributor head 19. Fuel advanced by the screw 13 is moved over the distributor head 19 into the zone of action of the pressure fluid blasts issuing from the jet openings 21, which blasts serve to project the fuel across the plate 24 over the fire. Adjustable deflector vanes 25 and 26 constitute continuations of the sidewalls 16 and 17, respectively, and each may be adjusted and fixed in one of a number of positions to vary the distribution of the fuel.

A novel, improved and simplified construction is provided for detachably supporting the distributing table 24 from the distributor head 19. A lip 27 is formed with and extends outwardly from the upright face 22 of the distributor head immediately beneath the jet openings 21. A ledge 28 formed with the distributor head 19 is beneath and spaced apart from the lip 27 and extends forwardly beyond the free side of the lip 27. The ledge 28 has formed at its free side an upstanding lip 29 terminating a vertical distance below the lip 27 equal to the thickness of the rearward portion of the distributing table 24.

The rearward side of the table 24 extends

beneath the lip 27 and abuts the wall 30 included between the lip 27 and the ledge 28 and, between its rearward and forward sides, the table 24 rests on the upstanding lip 29. The weight of the 5 table overhanging the lip 29 restrains upward displacement of the table and the lip 27 and ledge 28 prevent the table from dropping into the firebox. Since the vertical distance between the lip 27 and the upper edge of the lip 29 is approximately the thickness of the rearward portion 10 of the table, the table normally assumes a substantially horizontal position.

Fore and aft movement of the distributing table is prevented by the lugs 31 which depend 15 from the underside of the table 24 and fit closely adjacent the inner surface of the lip 29 when the table is in operative position and by reason of the fact that the rearward side of the table abuts the wall 30. Lateral movement of the table is prevented 20 by the vane 32 which is formed with the ledge 28 and fits between the lugs 31 when the table is in position.

Provisions have been made whereby the table 24 can be conveniently placed in operative position 25 and similarly disengaged from the distributor head and removed when it is desired to do so for purpose of repair, replacement or other reasons. The wall 30 and the inner surface of the lip 29 are curved and described on a common 30 radius. The side of the table 24 abutting the wall 30 and the sides of the lugs 31 contacting the inner surface of the lip 29 are likewise curved and described on such common radius. This permits the table 24 to be raised about its rearward 35 side as a pivot and to be removed from engagement with the distributor head when the lugs 31 have cleared the upper edge of the lip 29. Normally such upward movement is restrained by the overhanging weight of the table 40 24, so that for all practical purposes the table is securely and immovably engageable with the distributor head 19. The height to which the table must be raised before it can be disengaged from the head is determined by the height of the lugs 31. The higher the lugs 31 are the 45 higher the table must be raised in order that the lugs 31 clear the upper edge of the lip 29. For practical purposes the distance to which the table must be raised before it can be disengaged is such as to eliminate the possibility of accidental 50 disengagement. It will be obvious that neither the entire contacting surfaces nor all of them need necessarily be curved to effect the above result, it having been shown in this manner in 55 the drawings for purposes of illustration and such modifications as effect the same result with fewer curved surfaces or with partially curved surfaces come within the purview of my invention.

60 Figures 4, 5 and 6 show a slightly modified form of the invention, differing from the preferred form in that downward movement of the table 40 about the support ledge and lip 41, 42 is prevented by the spaced tongues 43 and 44 which depend 65 from the underside of the table and extend rearwardly beneath the distributor head 45. The tongues 43 and 44 are spaced apart a distance sufficient to permit the ledge 41 to pass therebetween when placing the table in position.

70 From the foregoing it will be understood that the rear section of the distributing mechanism need not be made in the form of a chambered distributor head but may constitute the rear section of a two section distributor plate over which fuel 75 may be propelled by pressure fluid blasts dis-

charged from a point rearward thereof or in any other operative position.

I claim:

1. In a stoker, a distributing device arranged to permit fuel to pass thereover for distribution over a fire comprising separable rear and front sections, a ledge formed with said rear section and extending forward of its front face, said ledge forming a support for said front section, said rear section being provided with means engaging the 10 rearward side of said front section for preventing upward displacement of the rearward side of said front section, a lug depending from the under side of said front section engaging said ledge, said lug and said ledge having contacting 15 surfaces at least one of which is curved permitting upward swinging movement of said front section about its rearward side, said front section being disengageable from said rear section upon disengagement of said lug and ledge. 20

2. In a stoker, a distributing device arranged to permit fuel to pass thereover for distribution over a fire comprising separable rear and front sections, a lip formed with said rear section and extending forward of its front face, a ledge 25 formed with said rear section beneath and spaced apart from said lip and extending forwardly beyond the free side of said lip, said ledge having at its free side an upturned portion, said front section resting between its forward and rearward 30 sides on said upturned ledge portion, the rearward side of said front section extending beneath said lip for preventing displacement of said front section by reason of its overhanging weight, a lug depending from the underside of said front 35 section engaging the inner surface of said upturned ledge portion preventing forward movement of said front section with respect to said rear section, said lug and the inner surface of said upturned ledge portion being arranged to 40 permit upward swinging movement of said front section about its rearward side.

3. In a fuel distributing device, a distributor head having a front face, jet openings in said front face, a lip extending forward of said face, a 45 ledge formed with said distributor head, said ledge being beneath and spaced apart from said lip and extending in the same direction and beyond the free side of said lip, said ledge at its free side having an upturned portion, a distributing 50 table resting between its rearward and forward sides on said upturned ledge portion, the rearward side thereof extending beneath said lip, a lug depending from the underside of said table 55 contacting the inner surface of said upturned ledge portion, the wall included between said lip and said ledge and the inner surface of said upturned ledge portion being curved and formed on a common radius, the rearward side of said table and said lug contacting the said curved 60 walls respectively and forming therewith a pivot about which the table can be moved.

4. In a fuel distributing device, a distributor head having a front face, jet openings in said front face, a lip extending forward of said face 65 beneath said jet openings, a ledge formed with said distributor head spaced beneath and apart from said lip and extending in the same direction and beyond the free side of said lip, said ledge at its free side having an upturned portion 70 terminating a vertical distance below said lip, the wall portion included between said lip and said ledge and the inner surface of said upturned ledge portion being curved and formed on a common radius, a distributing table, the rearward 75

portion of said table extending beneath said lip, said table resting on said upturned ledge portion between its forward and rearward sides, the weight of said table overhanging the upturned

5 ledge portion normally preventing upward displacement of the forward edge of said table, a lug depending from the under side of said table arranged to fit closely adjacent the curved surface of said upturned ledge portion preventing 10 forward displacement of the table, the rearward side of said table and the surface of said lug contacting the curved surface of said upturned ledge portion being curved and formed on the same radius as said curved surfaces whereby said 15 plate can be inserted in position by pivoting it about its rearward side.

5. As an article of manufacture, a distributor head for a stoker having a front face, jet openings in said front face, a lip extending forward 20 of said front face, a ledge beneath and spaced apart from said lip extending in the same direction and beyond the free side of said lip, said ledge at its free side having an upturned portion terminating a vertical distance below said 25 lip.

6. As an article of manufacture, a distributor head for a stoker having a front face, jet openings in said front face, a lip extending forward of said front face, a ledge beneath and spaced 30 apart from said lip extending in the same direction and beyond the free side of said lip, said ledge at its free side having an upturned portion terminating a vertical distance below said lip, the wall portion included between said lip and 35 said ledge having an arcuate surface.

7. As an article of manufacture, a distributor head for a stoker having a front face, jet openings in said front face, a lip extending forward of said front face, a ledge beneath and spaced 40 apart from said lip extending in the same direction and beyond the free side of said lip, said ledge at its free side having an upturned portion terminating a vertical distance below said lip, the inner surface of said upturned ledge 45 portion having an arcuate surface.

8. As an article of manufacture, a distributor head for a stoker having a front face, jet openings in said front face, a lip extending forward of said front face, a ledge beneath and spaced 50 apart from said lip extending in the same direction and beyond the free side of said lip, said ledge at its free side having an upturned portion terminating a vertical distance below said lip, the wall portion included between said lip and 55 said ledge and the inner surface of said upturned ledge portion being curved and formed on the same radius.

9. As an article of manufacture, a distributing table for a stoker having a surface across 60 which fuel passes for distribution, the rearward side of said table being curved, a lug depending from the under side of said table nearer its rearward than its forward side, the forward surface of said lug being curved, said forward surface and the curved edge of said table being 65 formed on a common radius.

10. As an article of manufacture, a distributor head for a stoker having a front face, jet openings in said front face, a ledge beneath said jet openings extending forward of said front face, at least a portion of the wall included between 5 said jet openings and said ledge being curved, said ledge at its free side having an upturned portion, the inner surface of said upturned ledge portion being curved, said curved surfaces being formed on the same radius. 10

11. As an article of manufacture, a distributing table for a stoker having a surface across which fuel passes for distribution, the rearward side of said table being curved, a lug depending from the under side of said table, the surface 15 of said lug facing the front of said table being curved, said curved surface and the curved side of said table being formed on a common radius and ledges depending from the under side of said table and extending rearwardly beyond the 20 rearward side of said table.

12. In a stoker, a distributing device arranged to permit fuel to pass thereover for distribution over a fire, comprising separable rear and front sections, a ledge formed with said rear section 25 and extending forwardly of its front face, said ledge forming a support for said front section, said rear section being provided with means engaging the rearward side of said front section for preventing upward displacement of the rear- 30 ward side of said front section, means depending from the under side of said front section engaging said ledge for preventing forward displacement of said front section, said front section being arranged to permit upward swing- 35 ing movement thereof about its rearward side and being disengageable from said rear section upon disengagement of said depending means and said ledge.

13. In a stoker, a distributing device arranged 40 to permit fuel to pass thereover for distribution over a fire comprising separable rear and front sections, ledge-like means formed with said rear section and extending forward of its front face forming supporting means for said front section, 45 means formed with said rear section and extending forward of its front face above said ledge-like means and above the fuel supporting surface of said front section engaging the rearward portion of said front section for preventing up- 50 ward displacement of the rearward portion of said front section and downward displacement of the forward portion of said front section, said front section being arranged for upward swing- 55 ing movement about its rearward portion and being disengageable by such swinging movement from said rear section, and means formed with and extending in a substantially vertical direction from the rearward portion of said front section, said means being engaged by one of the 60 means extending forward of the front face of said rearward section for preventing forward displacement of said front section with respect to said rearward section. 65
